N. Y., a corporation of Massachusetts

Application May 24, 1934, Serial No. 727,312

4 Claims. (Cl. 200—166)

The present invention relates to electrical circuit controllers, and has for its object to provide an improved contact structure for devices of this character that is adapted to handle the flow of electrical currents with uniform contact pressure and without destructive arcing.

The present invention relates particularly to a circuit controller of the type employing a pivoted member adapted by its movement to carry contacts into and out of operative relation with cooperating stationary contacts. The improved contact structure of the invention is incorporated in the movable member so as to always engage the stationary contacts with an even pressure, and in operation, is characterized by the substantial elimination of arcing, high current carrying capacity, as well as the absence of any flexible leads for conducting current to the movable contacts. The above and other advantageous features of the invention will hereinafter more fully appear from the following description with reference to the accompanying drawing, in which:—

Fig. 1 is a view in side elevation of a circuit controller embodying the invention, with the contacts in non-current carrying position.

Fig. 2 is a view similar to Fig. 1, showing the contacts in current carrying position.

Fig. 3 is a view in front elevation, on an enlarged scale, of the contact structure removed from the circuit controller.

Fig. 4 is a rear elevation of the parts shown in Fig. 3.

Fig. 5 is a vertical sectional view along the line 5—5 of Fig. 3.

Fig. 6 is a sectional view similar to Fig. 5, showing the contacts of the controller in engagement.

Fig. 7 is a view similar to Fig. 3, showing a modification of the invention.

Fig. 8 is a sectional view along the line 8—8 of Fig. 7.

Fig. 9 is a view in side elevation of a circuit controller embodying the modified contact construction of Fig. 7.

Like reference characters refer to like parts in the different figures.

Referring first to Figs. 1 and 2, the invention is shown, for purposes of illustration, as being embodied in a circuit controller of the relay type, the essential elements of which comprise an insulating base 1 carrying a magnetic core 2, one leg of which is surrounded by an energizing winding 3. A magnetic armature 4 pivotally supported on the lower end of the other core leg is adapted to be raised upon energization of the winding 3

and held in the position of Fig. 2, deenergization of the winding 3 permitting the armature 4 to fall back into the position of Fig. 1 under the influence of gravity. The armature 4 carries one or more upwardly extending arms 5, and each arm 5 is provided at its free end with a contact structure 6 embodying the present invention and adapted to cooperate with spaced stationary contacts 7 and 8 mounted on the base 1, in a manner which will next be described.

As best shown in Figs. 3, 4 and 5, the contact structure 6 consists of a plate 9 carrying a pair of contacts 10 having substantially the same spacing as the stationary contacts 7 and 8. The contacts 10 extend through openings 11 provided in the upper end of the arm 5, which openings 11 are of appreciably larger diameter than the contacts 10. The plate 9 also provides a central opening 12 which freely receives a pin 13 mounted on the arm 5 between the openings 11. The opposite end of the pin 13 provides a head 14 and a spring 15, surrounding the pin 13 between the head 14 and the plate 9, exerts a pressure tending to hold the plate 9 in contact with the arm 5.

With the winding 3 deenergized and the armature 4 occupying the position of Fig. 1, the plate 9 carrying the contacts 10 is held in engagement with the arm 5 by the pressure of the spring 15. Upon energization of the winding 3, the armature 4 is drawn upwardly to the position of Fig. 2, thereby carrying the contacts 10 on the arm 5 into engagement with the stationary contacts 7 and 8. Owing to the fact that the arm 5 is still inclined somewhat from the vertical, as the contacts 10 engage the stationary contacts 7 and 8, it follows that the lower contact 10 will engage the contact 8 somewhat in advance of engagement of the contact 7 by the upper contact 10.

When this occurs, the plate 9 yields against the pressure of the spring 15, and separates from the arm 5 as the contacts come into complete engagement. The yielding of the plate 9 is shown on a somewhat exaggerated scale in Fig. 6, from which it is apparent that there results a very even engagement between the faces of the contacts 7, 8 and 10. Since the plate 9 is, in effect, floating at the end of the movable arm 5, the contacts 10 are adapted to adjust themselves to the stationary contacts 7 and 8, with their engaging faces always in parallel relation and with a substantial elimination of arcing due to uneven wear of the contact surfaces. Upon deenergization of the winding 3 and dropping of the armature 4, the contacts 10 disengage the contacts 7 and 8 in the reverse order of their engagement.

with the contact faces remaining substantially parallel until the final separation.

Referring now to Figs. 7 and 8, there is shown a modification of the invention in which spaced arms 16 carried by the armature 4 are adapted to carry between them a contact member 17 adapted to cooperate with stationary contacts on opposite sides thereof, as indicated in Fig. 9. The upper ends of the arms 16 provide aligned openings 18 and pairs of contacts 19 and 20 carried by the member 17 project through these openings 18. Normally, the contact member 17 is yieldingly clamped between the arms 16 by the action of springs 21 surrounding a pin 22 projecting beyond the arms 16 on either side.

As best shown in Fig. 9, the circuit controller provides spaced stationary contacts 1' and 8' mounted on the base 1 and a second pair of stationary contacts 23 and 24 mounted on a bracket 20 25 carried by the core 2. With the armature 4 in its lower position due to deenergization of the winding 3, the right hand contacts 20 are held in engagement with the stationary contacts 23 and 24 by the weight of the armature 4, which 25 may be augmented by the provision of an extra weight 4a. With the contacts 20 engaging stationary contacts 23 and 24 as indicated in dotted lines in Fig. 8, it is obvious that the contact member 17, floating between the upper ends of the 30 arms 16, is adapted to adjust itself to insure proper engagement between the contact surfaces. Upon lifting of the armature 4 due to energization of the winding 3, separation of the contacts 20 from the stationary contacts permits the contact member 17 to resume its floating position between the arms 16. Therefore, engagement of the left hand contacts 19 with stationary contacts 7' and 8' is also accompanied by self-adjustment of the member 17 to insure uniform 40 pressure between the engaged contact surfaces.

From the foregoing, it is apparent that by the present invention there is provided an improved contact structure for circuit controllers characterized by its ability to maintain even contact 45 pressure at all times with a substantial elimination of arcing and increased current carrying capacity. Furthermore, since the floating contact members 8 and 17 are adapted to bridge both sides of a circuit, including the spaced stationary 50 contacts, the need for flexible leads for conducting current to the movable contact members is entirely eliminated, nor is there any necessity for

making the movable arms 8 and 16 of conducting material.

We claim:

1. In a device of the class described, the combination with spaced stationary contacts and a pivotally mounted arm providing openings near its free end and movable toward or away from said stationary contacts, of a plate freely supported on said arm, a spring normally maintaining said plate in engagement with said arm and contacts carried by said plate and extending through said arm openings for engagement with said stationary contacts, said plate by its free and yieldable mounting on said arm permitting self-adjustment of the engaged contacts independently of said arm. 15

2. In a device of the class described, the combination with opposed pairs of stationary contacts and a pivotally mounted member providing openings near its free end and movable toward or away from either pair of said stationary contacts, of a plate yieldingly supported on said pivoted member and providing oppositely extending spaced contacts movable freely in said openings for cooperation with said fixed contacts. 20

3. In a device of the class described, the combination with oppositely disposed pairs of spaced stationary contacts and a pivotally mounted member carrying spaced arms providing aligned openings near their free ends, of a contact structure mounted between said arms at their free ends and carrying oppositely extending contacts movable freely through said arm openings for cooperation with either pair of said stationary contacts, and means for pressing said arms together for maintaining said contact structure in position. 30

4. In a device of the class described, the combination with spaced stationary contacts and a pivotally mounted arm of relatively stiff material providing openings near its free end and movable toward or away from said stationary contacts, of a pin projecting from said arm between said openings, a plate loosely mounted on said pin and yieldingly maintained in engagement with said arm, and contacts carried by said plate extending freely through the openings of said arm for self-aligning engagement with said stationary contacts. 45
